Patented May 28, 1918.

Inventor
August Seibert

By his Atty. Charles G. Hendley

UNITED STATES PATENT OFFICE.

AUGUST SEIBERT, OF NEW YORK, N. Y.

SPINE-PROTECTOR.

1,267,598.

Specification of Letters Patent. Patented May 28, 1918.

Application filed February 7, 1918. Serial No. 215,785.

To all whom it may concern:

Be it known that I, AUGUST SEIBERT, a citizen of the United States, and a resident of the city, county, and State of New York, 5 have invented a certain new and useful Spine-Protector, of which the following is a specification.

Under modern modes of dress of the human body the spinal cord is exposed to cold and as the principal nerves which supply the extremities of the body center in the spinal cord any exposure of the latter or failure to maintain sufficient warmth at this vital center materially affects the circulation throughout the whole body. The bony processes of the spinal column are interspersed by thin loose tissue covered by skin alone, which affords no protection against the loss of body heat at this most 20 vital part. The muscles of the back adjacent the spinal column form ridges on each side, causing the spinal column to lie in a groove extending from a point between the shoulder blades downwardly, and the more 25 the back muscles are developed the deeper this groove becomes. The clothes generally worn upon the human body cover the spinal column but they do not ordinarily touch or press against it, unless it be while the back is 30 pressed against the back of a seat when the person is sitting down. In the act of rising from a seat and during many of the ordinary movements of the body cold air is drawn into the space between the clothing 35 and the spinal column, causing a loss of body heat at the nerve center, and this is one of the principal causes of chills.

The object of my invention is to provide a device adapted to be worn on the human 40 body, which will press into the back groove and either directly touch the surface of the spinal column or else press the undershirt into contact therewith. The purpose of this is to keep the protector or shirt pressed 45 against the surface of the spinal column so as to fill up the groove of the back or prevent cold air from being sucked or drawn in across the spinal column. I have found that where the present protector is made as 50 a detachable article to be worn over the undershirt the body temperature may be kept high during extremely cold weather and

with much lighter clothing than what would be required if the present device were not used. The effect of wearing the protector is 55 to not only keep up the body temperature at the spinal column but to keep the body warm throughout by its action on the blood circulation at the nerve center.

One object of my invention is to provide 60 a device for the above stated purposes, which will be convenient to wear, which will be inexpensive and washable and in the fullest embodiment of my invention, a device which may be readily applied or removed as 65 weather conditions vary.

In the drawing forming part of this application—

Figure 1 shows a back view of a person wearing the protector between the outer and 70 under shirt and showing how the suspenders may serve to press the protector against the back,

Fig. 2 is a plan view of the protector removed,

Fig. 3 is a cross sectional view, taken on the line 3—3 of Fig. 2, and

Fig. 4 is a sectional view showing the construction of the spinal column and the manner in which the protector fills the back 80 groove.

The protector is preferably made as a detachable device though in the broadest aspect of my invention it may be incorporated as part of a garment, for instance, as part 85 of the undershirt, though there are many advantages in making the article independent of any garment. The form or shape may be varied to a great extent but the principal feature is the provision of a protruding portion adapted to fit into the back groove so as to lie close to or press against the spinal column.

In the drawing I have shown a base or foundation consisting of a strip of fabric 1. 95 This is of sufficient length to reach from a point near the shoulders, preferably from the collar band of the undershirt down to the end of the spinal column of the average male person, but the length may be varied 100 to suit the particular requirements of persons above or below the average height. The foundation 1 is shown as having a soft upper section 2 above the protruding member,

which may be fastened to the undershirt, as by means of the safety pins 3. Below the section 2 the base is made narrower at 4 in order to lie in the narrower space between the shoulder blades, as it is preferable that the base should not extend over the shoulder blades in order that it shall not interfere with their freedom of movement and in order that the device may be retained in proper position. From the narrower portion 4 the base gradually broadens out to the widest portion 5 which comes about on a line with the abdomen. From the widest portion 5 the base gradually tapers at 6 to a somewhat pointed end 7.

At the corners on the widest portion 5 I have attached tapes 8 which are adapted to be brought around the abdomen and their ends may be tied at the front, as shown dotted at 9 in Fig. 1. These tapes serve to hold the base snugly against the back.

The entire base may consist of one or more pieces of fabric and I prefer to finish the entire edge with a hem 10.

The protruding member for filling up the back groove may be made in various ways but the one shown herein is very inexpensive and efficient. There is a strip of fabric 11 attached by the double row of stitches 12, 13 along the middle portion of the base 1 and from the point 14 just below the top member 2 down to the point 15. This strip is preferably folded upon itself to provide the proper structure and this folding operation may be accomplished simultaneously with the stitching operation, upon sewing machines which are now on the market. The strip 11 may consist of an inner layer 16 having its edge unstitched, the strip being turned back upon itself at 17, where it is secured by the line of stitches 12, and the turning back of the strip upon itself forms a second layer 18. At 19 the fabric is turned in upon itself to form a third layer, 20, which lies between the first layer and the second layer, the looped edge 19 being secured by the line of stitches 13. The strip 11 stands out from the base between the rows of stitches and I arrange within the space between the base and strip a filler 21 composed of a number of strands of thread or cord arranged lengthwise of the protector. The particular kind of filler is not vital except that it should be sufficiently pliable to be pressed into the back groove and to bend readily with the movements of the body.

When the device is worn on the body the suspenders may be utilized for keeping the protector pressed against the back. As shown in Fig. 1, the protector may be worn between the undershirt and outer shirt and the suspenders cross over near the center of the protector. Thus the suspenders press upon a considerable portion of the protector

and assist in keeping the latter pressed 65 against the back.

In Fig. 4 I have shown a cross section to illustrate the lack of natural protection to the spinal column and the way the present device projects into the groove of the back 70 and either directly touches the skin over the spinal column or else presses the undershirt into contact therewith. In this view I have shown a portion of the spinal column consisting of the vertebrae 22. Aside from the 75 tissues between these their only natural protection is the skin. When the present device is worn upon the back, the base 1 lies against the muscles of the back and the protrusion formed by the strip 11 and its filler extends 80 into and fills the groove over the spinal column. If the protector is worn over the undershirt the latter is pressed by the protruding member directly against the skin and the remainder of the groove is filled by 85 the protrusion of the protector. When the person rises up from a seat or bends the body in walking, etc., cold air is not drawn in between the clothing and the body to pass along the spinal column but the shirt or the 90 protector is pressed at all times into contact with the body along the back groove. By making the protector as a detachable device it may be readily carried in the pocket or in the soldier's pack and it can be worn only 95 during such times as weather conditions make it desirable. The device is preferably made of washable material so that it may be readily washed in its entirety.

Having described my invention, what I 100 claim is:

1. A device for the purpose described comprising a base or the like adapted to be worn upon the back of the human body and a protruding member extending lengthwise of the back and adapted to project into the groove of the back for the purpose set forth.

2. A device for the purpose set forth comprising a base or the like of pliable material 110 adapted to be worn upon the back of the human body and a protruding member of pliable material extending lengthwise of the back and adapted to project into the groove of the back for the purpose set forth. 115

3. A device for the purpose set forth comprising a base or the like of pliable material adapted to be worn upon the back of the human body a strip of pliable material secured to said base to form a pocket between 120 the base and said strip extending along the line of the spinal column and a filler in said pocket to form a protrusion adapted to extend into the back groove of the body when said base is worn upon the back.

4. A device for the purpose set forth comprising a base consisting of a comparatively wide top portion having means for attach-

ment to the undershirt above the center line of the shoulder blades, a narrower portion below said wide portion, a wider portion below said last mentioned portion, means attached to said latter wide portion adapted to encircle the body to hold said base against the back and means forming a protrusion on

10 said base extending lengthwise thereof and adapted to project into the groove of the back for the purpose set forth.

Signed at the city, county, and State of New York, this 29th day of January, 1918.

AUGUST SEIBERT.
